UNITED STATES PATENT OFFICE.

ALMON B. CALKINS, OF BELLEVILLE, NEW JERSEY, ASSIGNOR TO AMERICAN MATCH MANUFACTURING COMPANY, OF NEW YORK, N. Y., A CORPORATION OF NEW JERSEY.

SPLINT-CARRIER.

No. 845,447.

Specification of Letters Patent.

Patented Feb. 26, 1907.

Application filed May 26, 1906. Serial No. 318,866.

To all whom it may concern:

Be it known that I, ALMON B. CALKINS, a citizen of the United States of America, and a resident of Belleville, county of Essex, State of New Jersey, have invented certain new and useful Improvements in Splint-Carriers, of which the following is a specification, reference being had to the accompanying drawings, forming a part thereof.

10 My invention relates to improvements in splint-carriers, and particularly to improvements in carrier-chains which form the supporting elements for individual splint-grippers.

15 The main object of my invention is to simplify and lessen the cost of construction of carrier-chains of this description, while providing that the various parts shall be, so far as is possible, interchangeable, easy of access, 20 and readily assembled and disassembled.

To these ends my invention consists in certain novel combinations of parts and details of construction, as will be hereinafter more fully pointed out.

25 To the end that my invention may be thoroughly understood I will describe in detail an embodiment thereof, having reference to the accompanying drawings, illustrating same, and will then point out the novel features in claims.

30 In the drawings, Figure 1 is a top view of a portion of a carrier-chain embodying my invention, with certain parts broken away and other parts removable. Fig. 2 is a view in side elevation of the same. Fig. 3 is a view in transverse section substantially upon the plane of the line 3 3 of Fig. 1. Fig. 4 is a perspective view of one of the links detached.

35 The main elements of the chain herein are side links 10 and transverse plates 11 12. Each section of the chain comprises one each of the transverse plates 11 and 12 and a plurality of links 10, supporting the said plates and constituting members by which the several sections are pivotally connected together. All the links 10 are similar, each said link comprising a thin plate having a central hole 13 therethrough, side holes 14 14, rounded ends 15, flat upper and lower edges 16, and upper and lower projecting tongues 17. The plates 11 11 have bifurcated end portions 18, which rest upon the surfaces 16 and receive the uprising tongues within them.

This arrangement of plates and links properly spaces the upper and lower plates 11 and 12 from each other and also properly spaces the links at opposite ends apart. The plates 11 and 12 are suitably fastened together, as by rivets 19, and thimbles or spacing-pieces 20 may also be employed at different points throughout the length of the plates—as, for instance, wherever the rivets are used—as may be desired.

The plates 11 and 12 form supports for individual splint-grippers 21, which *per se* form no part of the present invention, the said grippers being conveniently held in place by a cover-plate 22, secured to the plate 11 by screws 23, which cover-plate clamps projecting lips 24 of the grippers 21 between itself and the said plate 11.

The links 10 are preferably arranged in alternate relation, so as to even up the strain, single links 10 alternating with pairs of links, as clearly shown in the drawings, and a single link at one end of a pair of plates being opposite to a pair of links at the other end. The several links are pivoted together by means of pintles 25, received within the openings 14 and riveted at their outer ends. The central openings 13 of each pair of links receive trunnions 26, which are suitably secured thereto. At certain points rods 27 may extend all the way across the chain from the links at one end of the plates 11 12 to the links at the other end thereof in order to lend further rigidity to the chain; but in practice I have not found that such bars are always necessary, as the connection of the bifurcated ends of the plates with the uprising portion of the links is usually quite sufficient for this purpose. I may bend over the ends of the plates, as shown in Fig. 3, in order to offset any tendency of the links to spread, as will be well understood.

95 From the foregoing it will be seen that I have provided a chain composed of but few parts, and those inexpensive to build, readily assembled, and easy of access and removal when required. As all the links are similar, they are all interchangeable, so that any damage thereto may be easily and quickly repaired. To obtain access to any of the individual grippers, it is only necessary to remove the screws 23 of the cover-plates of any section, when all the individual grippers of

that section may be immediately removed and replaced. To remove a section entirely without affecting the rest of the chain, it is only necessary to bend up the projecting ends 5 of the bifurcated portions 18 of the plates, which may be readily done, as the plates are preferably composed of a soft flexible iron or machinery-steel. A new section may be inserted in a similar manner by first bending up 10 the ends of the plates, inserting the sections, and then bending them back again, as will be readily understood.

What I claim is—

1. A carrier-chain comprising upper and lower splint-gripper-supporting transverse plates having bifurcated ends, and links having upper and lower projections fitted to said bifurcated ends, substantially as specified.
2. A carrier-chain comprising upper and lower splint-gripper-supporting transverse plates having bifurcated ends, links having upper and lower projections arranged between said plates, with the projections fitted to and projecting through said bifurcated 20 ends, the projecting end portions of said plates bent over to prevent spread of said links, substantially as specified.
3. A carrier-chain comprising upper and lower splint-gripper-supporting transverse 25 plates having bifurcated ends, and links having upper and lower projections received within the bifurcated ends thereof, and trunnions supported and carried by said links.

plates having bifurcated ends, links disposed between the said plates, having upper and lower projections received within the bifurcated ends thereof, and trunnions supported and carried by said links.

4. A carrier-chain comprising upper and lower splint-gripper-supporting transverse plates having bifurcated ends, links disposed between the said plates, having upper and lower projections received within the bifurcated ends thereof, trunnions supported and 40 carried by said links, and spacing-bars 27 between the links at opposite ends of said plates.

5. A carrier-chain comprising upper and lower plates 11 and 12 having bifurcated ends 45 18, links 10 at the opposite ends of said plates spacing them apart, and having projections 17 received within the bifurcated ends 18, rivets 19 securing the plates together, trunnions 26 supported by the links, and pintles 50 25 pivoting the links together.

In witness whereof I have hereunto set my hand this 21st day of May, 1906.

ALMON B. CALKINS.
